[57] CLAIM

The ornamental design for a parking curb reinforcing bar support, substantially as shown and described.

DESCRIPTION

FIG. 1 is a top plan view of a parking curb reinforcing bar support showing a design in accordance with my invention;

FIG. 2 is a front elevational view;

FIG. 3 is a left end elevational view;

FIG. 4 is a right end elevational view;

FIG. 5 is a bottom plan view;

The rear view is a mirror image of the front view and is therefore, not shown.
